FIG. 3

UNITED STATES PATENT OFFICE

2,239,721

PRINTING TELEGRAPH APPARATUS

Howard L. Krum, Beverly Hills, Calif., assignor
to Teletype Corporation, Chicago, Ill., a corpora-
tion of Delaware

Application December 30, 1936, Serial No. 118,237
Renewed February 26, 1940

30 Claims. (Cl. 178—35)

The present invention relates to printing telegraph apparatus and more particularly to telegraph apparatus wherein characters are printed upon a tape.

The principal object of the invention is to provide a simple, efficient, and relatively inexpensive printing telegraph machine operable under the control of permutation code combinations of signaling conditions.

According to the present invention, there are provided selectable instrumentalities controlled by a single magnet selector mechanism, which, in turn, control the operations of type wheel and printing mechanisms. There is mounted on the main operating shaft, which is connected to the motor for continuous rotation therewith, a sleeve operatively connected to the shaft through a ratchet or grab clutch mechanism, said sleeve carrying a set of code discs which are fixed thereto, as well as a series of cams, a driving ratchet, and a type wheel. The code discs are notched in permuted manner determinative of the positions of the characters on the type wheel so that when a series of seeker levers, permutably selected by means of a single magnet pin barrel selector, are actuated simultaneously, upon finding an alignment of wards and notches corresponding to the permuted arrangement of said levers, a printing mechanism is operated at the proper time to effect printing in accordance with the received character signal.

In one form of the invention, the type wheel is fixed to the aforementioned sleeve and has associated therewith a ratchet wheel, also fixed to said sleeve, and cooperative with said ratchet wheel is a spring actuated pawl, which when released, is biased toward the ratchet wheel to be impulsively actuated thereby to effect, through interconnecting linkage, the infringement of a platen against the type wheel to produce printing without interrupting the rotation of the type wheel. In another form of the invention, toggle printing is provided, in which event the type wheel is yieldably connected to the aforementioned sleeve for the reason that, as printing occurs, a pointer carried by the printing hammer cooperates with a star wheel to momentarily stop the type wheel during the printing operation, the type wheel thereafter being rotated to its normal stop position, with the blank portion of the type wheel presented to the printing hammer.

The above and other objects of the invention will be apparent from the following description when taken in conjunction with the accompanying drawings, wherein like reference characters

designate similar parts throughout the several views, in which—

Fig. 1 is a fragmental elevational view of the apparatus according to the present invention;

Fig. 2 is a partial top view of the apparatus shown in Fig. 1;

Fig. 3 is a fragmentary side elevational view of the apparatus of the present invention;

Fig. 4 is a partial elevational view of the printer with the front plate removed, to show the selector mechanism;

Figs. 5, 6, and 7 are views of the selector mechanism in accordance with the present invention; and

Fig. 8 is a view showing an alternative form of printing mechanism.

The combination sending-receiving apparatus shown in Figs. 1 and 2 comprises essentially a printing unit indicated generally as 11 and a keyboard transmitting unit indicated generally as 12. In practice, of course, two or more of such apparatuses are interconnected in a telegraphic signal line for intercommunication. Although various forms of transmitting mechanisms may be employed, the one chosen to illustrate the present embodiment is in accordance with the transmitter mechanism disclosed in U. S. Patent No. 1,595,472. As shown in Figs. 1 and 2, the keyboard portion is provided with a set of keys 13 arranged similar to the well-known typewriter keyboard, and the key levers 14 associated with the keys 13 are pivotally mounted on a common shaft (not shown) and are spring held in normal horizontal position in well-known manner.

Key levers 14 extend over a number of pairs of code bars 15 and 16 included in the selecting mechanism which is of the form disclosed in U. S. Patent No. 1,884,753 granted to H. L. Krum. The bars 15 and 16 of each pair are supported (Fig. 1) at each end by T-shaped rocker arms 17 mounted on pivot rods 18. T-levers 17 are provided with offset lugs 19 and 21, which uphold the code bars 15 and 16, respectively, of the corresponding pair of code bars. The rocker arms 17 of each pair of code bars are pivoted to and reciprocate a permutation bar 22. Each key lever 14 is arranged to depress one of the code bars 15 or 16 of each pair of code bars and, through the medium of rocker arms 17 and bars 22, to lift the other code bars. The permutation bars 22 are set in characteristic combinations and for this purpose the code bars 15 and 16 are provided with notched upper edges, the bars of each pair being complements; that is, the high por-

tions of one bar are opposite the low portions of the other bar of the same general pair. It is also noted that the code and permutation bars have no normal position and are moved back and forth by the key levers 14. As is clearly apparent from Fig. 1, the bar 16 is lowered and the bar 15 is raised by certain key levers. Also, since each key sets the code bar in its individual combinational position, two keys cannot be completely depressed at the same time, and any attempt to do so will bring the code bars to their mid-position, which is, of course, a non-selecting position.

The T-levers 17 at the right-hand side of the unit 12 (as viewed in Fig. 1) are provided with vertically extending arms 23 which terminate in bifurcations adapted to embrace the lower extremity of the depending arm of individual locking latches 24. The series of locking latches 24 corresponding to the series of pairs of code bars 15 and 16 is rocked to either of two positions through the operation of said code bars. Associated with latches 24 are a corresponding series of contact levers 25 for making and breaking transmitting contacts 26. Contact levers 25 contact with individual contact cams 27 mounted on shaft 28. The shaft 28 is provided with a clutch mechanism, not shown, which is adapted to be controlled by a universal bar member substantially as set forth in Patent No. 1,595,472.

The operation of the transmitting unit consists essentially in the depression of a key lever 14 which effects the arrangement of the set of code bars 15—16 permutably in accordance with a predetermined code combination, the setting of which determines the position of the locking latches 24. The rotation of the cams 27 is initiated substantially simultaneously with the setting of the locking latches 24, and the locking loop 29 controlled by a cam 31 is permitted to 40 rotate in a counterclockwise direction (Fig. 1) to effect the locking of latches 24 during the transmitting cycle. The setting of the locking latches 24 determines whether the contact levers 25 shall or shall not be affected by their associated cams 27 to cause the opening or closing of their associated contacts 26 to transmit over a signal line to the receiving station a predetermined code combination of signaling impulses. The respective notches in the cams 27 are arranged in a helical progression so that upon the rotation of the cam assembly, the contacts 26 will be controlled successively. The apparatus herein disclosed is operated in accordance with an equal length letter code, in which each code combination is a permutation of marking and spacing conditions and is preceded by a start impulse and followed by a stop impulse, according to the familiar start-stop system.

The receiving portion 11 of the apparatus herein described comprises a receiving selector mechanism of a type similar to that disclosed in U. S. Patent No. 1,811,133 granted to E. E. Kleinschmidt, which is responsive to the signaling impulses transmitted to it through the transmitting contacts comparable to contacts 26 of the sending station. Since the normal condition of the signal line is a marking condition, the armature 33 of the selector magnet 32 remains in its actuated or attracted position as shown in Fig. 2. The selector magnet 32 is carried on a bracket 34 mounted on the housing of the transmitting portion 12. Also secured to bracket 34 is the member 35 to the extremity of which is pivoted at 36 the armature 33. The armature 33 is pro-

vided with a bifurcated actuating extension 37, Fig. 7, the bifurcated end of which fits into an annular channel 38 of the selector cam shaft 41. The shaft 41 is slidably journaled in a stationary bearing 42 which is supported upon the base housing 12. Formed integrally with the opposite end of shaft 41 is a bearing extension 43 which fits slidably into a suitable recess or bore formed in the end of the stud shaft 44. Stud shaft 44 is journaled for rotation in fixed bearing 45, and rigidly secured thereto and driven thereby is a trip cam 46 which is provided with a driving extension 47. Driving extension 47 is pivotally connected to cam shaft drive member 48 which, in turn, is articulated to cam shaft 41 by means of securing pin 49. The shaft section 44 is driven through a friction or slip clutch indicated generally as 51 (Fig. 3) which may be of any suitable construction and which is driven by a gear 52, rotatably carried on a stud shaft 53 mounted on bracket 54. Gear 52 meshes with and is driven by a pinion 55 which is mounted on the armature shaft 56 of a motor 57, which in operation rotates the shaft 56 at a predetermined and constant speed.

Secured to cam shaft 41 is a stop pin 58 which, in the position of parts shown in Figs. 4 and 7, engages a stationary stop projection 59 suitably supported from the framework of the mechanism. A series of selecting cams or pins 61 is arranged and equally spaced helically around the shaft 41 and is rigidly secured thereto. Depending upon the selective condition of shaft 41 (with reference to axial position) the cams 61 will successively engage cam portions 62 of selector levers 63, or actuating extensions 64 of latches 65 (Figs. 5, 6, and 7). With each selector lever 63 is associated a latch 65, and lever 63 normally tends to rotate in a clockwise direction, while latch 65 normally tends to rotate in a counterclockwise direction under the action of a common spring 66 extended therebetween. The selector levers 63 are pivotally mounted on a shaft 67, while the latches 65 are pivotally carried on a shaft 68. Selector levers 63 have no normal position but remain in their last selected position until a change is effected by their respective cams 61; for example, shaft 41 normally tends to rotate by the constant torque applied to it through the friction clutch 51, but is constrained against rotation by the arrestment of stop arm 58 by the stop lug 59, which arrestment is maintained so long as selector magnet 32 remains energized by marking current on the signal line.

Upon receipt of a start impulse, which effects the deenergization momentarily of the selector magnet 32, the armature 33 will be released and spring 69 will cause shaft 41 to be shifted downwardly, as viewed in Fig. 7, to effect disengagement of stop arm 58 from stop member 59 thereby initiating the rotation of shaft 41. Shaft 41 will be reciprocated axially in response to the succeeding signaling impulses and the corresponding energizations and deenergizations of the selector magnet 32; that is, if the first impulse after the start impulse is marking, the selector magnet will be energized as the first cam 61 approaches the corresponding selector lever 63 (Fig. 6), whereupon the first cam projection 62 will coat with the cam portion 62 of selector lever 63 to depress said cam lever against the action of spring 66 to permit counterclockwise movement of latch 65 and to cause the engagement of vertical projection 71 of lever 63 with the shoulder 72 of latch 65, as shown in Fig. 5,

also to bring projection 70 on lever 63 out of cooperative relation with associated seeker levers 60 for the purpose that will hereinafter appear.

On the other hand, if the first impulse after the start impulse is of spacing nature, the armature 33 will remain released due to continued deenergization of selector magnet 32, whereupon spring 69 will retain the shaft 41 downwardly (as viewed in Fig. 7) or outwardly (as viewed in Figs. 5 and 6) to cause the first cam projection 61 to coact with the actuating extension 64 of the latch 65 (Fig. 5) associated with the first selector lever 63 causing said latch to rotate slightly in a clockwise direction against the action of its spring 66 to permit rising or clockwise rotation of lever 63 and to bring vertical lug 71 of lever 63 into engagement with shoulder 73 of latch 65, as shown in Fig. 6, thereby bringing lug 70 into cooperative relation with associated seeker lever 60. The same selective operations will occur in response to the succeeding signaling impulses, and lever 63 or latch 65 will be directly actuated depending upon the nature of the signal impulse and the corresponding axial position of shaft 41. Since the stop impulse of the code combination is of marking nature, the selector magnet 32 will become energized as the stop arm 58 approaches the stop member 59 thereby causing armature 33 to be attracted and the shaft 41 to be actuated upwardly (as viewed in Fig. 7) bringing stop arm 58 directly in the path of stop lug 59, whereat it will remain until the subsequent reception of a start impulse.

Near the end of the cycle of rotation of shaft 41, the trip cam 46 cooperates with arm 14 of a clutch release lever 75 (Fig. 6) to initiate the rotation of the elements carried on the main operating shaft 76. Mounted on the main operating shaft 76 is the driving portion 77 of a grab clutch 78. Integral with driving portion 77 is a gear 79 which meshes with the pinion 55 on the motor shaft 56. Thus, gear 79 and driving portion 77 rotate continuously with the motor pinion 55. The grab clutch 78 comprises also a driven portion 81 which is slidably carried on shaft 76 and which is splined to a sleeve 82 (Fig. 2) to provide a driving connection with said sleeve. Clutch portion 81 is also provided with a flange 83 which has conformed thereon a cam surface 84 which coacts with a vertical arm 85 of the clutch release lever 75. When clutch release lever 75 is acted upon by cam 46, sufficient counterclockwise movement (as viewed in Fig. 6) will be imparted to clutch release lever 75 to effect the disengagement of arm 85 from the cam portion 84 whereupon the portion 81 of clutch 78 will be urged leftwardly (as viewed in Fig. 3) or upwardly (as viewed in Fig. 2) by a helical spring 86 carried on sleeve 82. In this manner, positive rotation is imparted to sleeve 86 during one cycle of rotation of clutch 78. Since arm 85 of clutch release lever 75 is normally biased toward the clutch portion 81 by a spring 87, the extremity of arm 85 will coact with the cam 84 to cause the disengagement of the clutch portion 81 from the clutch portion 77, and as arm 85 strikes the stop portion 88, further rotation of clutch portion 81 is prevented.

Integral with sleeve 82 is a sleeve 89 and fixed to sleeve 89 are a series of peripherally notched code discs 91, as well as cams 90, 92, 93, and 94. Sleeve 89 is fixed to shaft 76, which shaft is journaled in suitable bearings provided in brackets 54 and 95, bracket 95 being secured to front plate 75

96. In front of plate 96 and fixed to shaft 76 are a driving ratchet 97 and a type wheel 98.

The code discs 91 are so notched that each permutational setting of the series of seeker levers 60 will, upon sensing the periphery of the code discs, find first a permuted arrangement of wards and notches in the peripheries of the code discs individual to that setting of the seeker levers, and they will control the actuation of the printing mechanism. The character on the type wheel allotted to said setting of the seeker levers corresponds to the code thus first found in the discs. The seeker levers 60 are carried in a cradle 99, and the cradle 99 and seeker levers 60 are both pivotally carried on a common pivot shaft 101. The upper end of each seeker lever 60 is conformed with a nose portion 102 adapted to ride, during the seeking cycle, on the periphery of its respective code disc 91. At the upper end of each seeker lever 60 there is also provided a stepped portion 103 which coacts with an individual latch 104 carried on common pivot rod 105 mounted in vertical arms 106 of the cradle 99. Extended between latches 104 and seeker arms 60 are individual springs 107. Cradle 99 is also provided with a cam follower arm 108 which cooperates with the aforementioned cam 90.

Depending from the cradle 99 is an arm 109 which terminates in a laterally extending portion 111 (Fig. 3) which controls the printing function, as will presently appear. Pivotally carried at 112 (Fig. 4) above the latches 104 is a reset bail 113 which has an arm 114 which coacts with cam 92. The portion 111 of the depending arm 109 extends through the front plate 96 and cooperates with an arm 115 (Fig. 1) depending from a printing pawl arm 116 which, in turn, is pivotally carried at 117 on the printing hammer lever 118 pivoted at 119 to the front plate 96 and biased counterclockwise by a spring 120. Arm 115 of the printing mechanism is provided with shoulders 121 and 122 which cooperate with fixed detent 123 and latch 124, respectively. Arms 115 and 116 of the printing mechanism are normally biased upwardly by a spring 125, and arm 115 is normally urged into a counterclockwise direction by a spring 126 extended between arms 115 and 116. Detent 123 is adjustable in accordance with the tripping movement of portion 111 of arm 109 of cradle 99. Latch lever 124 is normally biased in a counterclockwise direction by a spring 127 against a stop 128. An adjustable stop 129 is provided for the printing hammer lever 118, and an adjustable stop 131 is also provided to coact with depending arm 132 of printing pawl arm 116.

As shown in Figs. 3 and 4, the laterally disposed portion 111 of depending lever 109 cooperates with a latch arm 133 pivoted at 134 to a bracket 135. Latch arm 133 is normally biased in a clockwise direction by a spring 136 and is provided with a shoulder 137 which coacts with portion 111 to limit the clockwise motion of cradle 99 imparted by a spring 138 (Fig. 2). For a purpose which will hereinafter appear, cradle 99 is rocked counterclockwise against the action of its spring 138 by the action of cam 96 (Fig. 4) upon arm 108. By this movement of cradle 99, portion 111 is actuated rightwardly, as viewed in Fig. 4, to coact with inclined cam surface 139 on latch arm 133 whereby latch arm 133 is cammed downwardly against the action of its spring 136 to bring shoulder 137 out of operative relation with portion 111, and causing shoul-

der 137 to become engaged with the shouldered portion 141 of the vertical arm of a latch lever 142 which is normally biased in a clockwise direction by a spring 143.

Counterclockwise rocking of cradle 99 will rotate also those seeker levers 60 which are cleared by lugs 70 on selector levers 63 positioned as shown in Fig. 5, but where a lever 63 is positioned as shown in Fig. 6 with lug 70 blocking a seeker 60, the seeker does not rotate and latch 104 is carried away from seeker 60 and the shoulders engage as shown in Fig. 4, thus transferring to seeker levers 60 that combinational code registered on levers 63.

When cam 90 passes arm 108, spring 138 will urge the cradle 99 clockwise to bring the nose portions 102 of the seeker levers 60 into contact with the peripheries of the code discs 91, and to bring portion 111 free of the shoulder 137 which is now latched down by the latching lever 142. Thereafter, when the seeker levers 60 have found an arrangement of wards and notches in the code discs 91 conforming to the particular setting of the seeker levers 60, said seeker levers will fall into the notches thereby causing cradle 99 to rock further in a clockwise direction in response to the action of its spring 138. This further clockwise movement of cradle 99 will carry portion 111 further in a leftward direction thus striking the vertical arm 141 of latch lever 142 to effect the disengagement thereof from shoulder 137. Simultaneously, portion 111 in its leftward movement disengages arm 115 from detent 123 (Fig. 1), permitting spring 125 to carry printing pawl arm 116 upwardly to bring the tooth 146 thereon into engagement with driving ratchet 97, which, due to its clockwise rotation during the printing cycle, will carry the pawl arm 116 sharply to the left, and due to the cooperative relation between pawl arm 116 and printing hammer lever 118, lever 118 will be actuated clockwise about its pivot 119 to bring its platen portion 144 against the proper character on the type wheel 98 to effect printing upon a tape 145.

During this printing operation, pawl arm 116 is carried leftwardly to bring depending arm 132 against stop 131, and further leftward movement of pawl arm 116 will cause said arm to be rotated counterclockwise about its pivot 117 to effect the disengagement of tooth 146 from the ratchet 91, and, due to the momentum imparted to pawl arm 116 by driving ratchet 97, pawl arm 116 will be rotated counterclockwise sufficiently to bring shoulders 121 or 122 into engagement with detent 123 or latch 124 respectively. Latch 124 is provided to prevent the pawl arm 116 from engaging the drive ratchet 97 more than once during a printing or operating cycle. To effect this result, arm 115, when it is driven downwardly against the action of spring 125, will be prevented from returning upwardly by spring 125 by the coaction of shoulder 122 and latch 124 if the portion 111 happens still to be in its leftward position to prevent the engagement of shoulder 121 with detent 123. Then, when portion 111 is restored to its position whereat it is again latched by latch arm 133, which occurs when seeker levers 60 are cammed out of the notches in discs 91 into which they have just previously fallen, spring 126 will urge arm 115 counterclockwise to disengage shoulder 122 from latch 124 and, since the lower edge of latch 124 is located slightly below the latching edge of detent 123, arm 115 will ride off of the latch 124 and onto the shoulder of detent 123. It is manifest that by this arrangement,

portion 111 is effective only once during each rotation of shaft 76 to trip arm 115 to effect printing, the portion 111 being immediately restored, due to the momentum caused by the camming-out action of seeker levers 60 by the notches in discs 91.

The tape 145 is supplied from a source not shown and is directed around a guide roller 147 (Fig. 1) thence over a feed roller 148 through a tape guide 149. Positioned above and cooperating with feed roller 148 is a pressure roller 151 carried on a lever 150 which is pivoted at 152 to front plate 96 and is normally biased into pressing engagement with the roller 148 by a spring 153. Spacing or stepping movement is imparted to roller 148 by the spacing mechanism shown in Fig. 4, which comprises a spacing lever 154 pivoted at 155 to the back of the plate 96. Spacing lever 154 is provided with an arm 156 which cooperates with the spacing cam 93 carried on shaft 76. With the spacing mechanism shown, the spacing movement occurs after printing so that during the major portion of the operating cycle, cam 93 causes spacing lever 154 to be rocked in a clockwise direction against the action of spring 157 to actuate pawl 158 downwardly to bring the pawl tooth into engagement with the next tooth on the ratchet wheel 159. Then approximately at the end of the printing cycle, the follower lever 156 is caused to fall off the high portion of cam 93, thus permitting spacing lever 154 to respond to the pull of spring 157 and to cause pawl 158 to rotate ratchet wheel 159 one angular step, which, through stud shaft 161, imparts corresponding angular motion to feed roller 148.

General operation

The relative positions of the parts during the period of rest are as shown in Figs. 1 to 7 inclusive, and the motor 51 is assumed to be continuously running, thus applying a constant torque to friction clutch 51 and causing constant rotation to the driving member 71 of the grab clutch 78. Upon reception of the starting impulse, the selector magnet 32 will be deenergized, thus permitting armature lever 33-37 to respond to the action of spring 69 associated with the selector cam shaft 41; that is, cam shaft 41 will be moved downwardly, as viewed in Fig. 7, to cause the disengagement of stop arm 58 from stop member 59, and initiation of rotation of cam shaft 41 is thus effected. Then in response to succeeding signal impulses of marking or spacing nature, cam shaft 41 will be reciprocated in a corresponding manner. Thus, as clearly set forth in aforementioned Patent No. 1,811,133, the selector levers 63 or latches 64 will be actuated by the cams 61 to cause a permuted setting of levers 63 in accordance with the received code signal.

Near the termination of the code cycle, cam 46 will actuate the clutch release lever 75 to disengage arm 85 from the driven portion 81 of grab clutch 78, whereupon through the engagement of portions 77 and 81, grab clutch 78 will cause the rotation of the elements mounted or carried on shaft 76; namely, code discs 91, cams 90, 92, and 93, driving ratchet 97, and type wheel 98. When shaft 76 is thus initiated into rotation, cam 92 coacts with reset bail 113 to rock the latches 104 clockwise to bring seeker levers 60 into the position shown in Figs. 5 and 6 whereat the seeker levers 60 are in their unselected positions, and latches 104 engage the lower shoulder of the series of shoulders 103. Immediately thereafter cam 90 actuates cradle 99 in a counterclockwise

direction against the action of its spring 138 to bring, first, the seeker levers 60, which through springs 107 will tend to follow cradle 99, into coaction with lugs 70 on selector levers 63 in such manner that those selector levers 63 which are in their elevated position, as shown in Fig. 6, will, through lugs 70 thereon, prevent the seeker levers individual thereto from rotating in correspondence with cradle 99. Those seeker levers 60 which are estopped by lugs 70 will resist the pull of spring 107, and accordingly, latches 104, which are constrained to follow cradle 99, will engage the upper shoulder of the series of shoulders 103. On the other hand, those seeker levers which are not estopped by lugs 70, as shown in Fig. 5, will continue to rotate with cradle 99, and latches 104 will continue to engage the lower of the series of shoulders 103.

Concurrently, as previously described, portion 111 of depending arm 109 of cradle 99 will cam the latch lever 133 downwardly by its action on cam surface 139 to permit latch lever 142 to engage shoulder 137 and lock the lever 133 in its downward position. Thus, after cam 90 passes arm 108, cradle 99 will respond to the pull of its spring 138 to bring the latched seeker levers 60 into contactual engagement with code discs 91, and as the code discs 91 continue to rotate, a permuted arrangement of wards and notches will eventually be found which corresponds to the permuted setting of the latched seeker levers 60, at which instant, when such setting is found, the selected seeker levers will fall into the notches corresponding thereto thus permitting spring 138 to actuate the cradle 99 slightly farther in a clockwise direction, whereupon portion 111 will be actuated leftwardly sufficient to disengage shoulder 121 of arm 115 from detent 123. Spring 125 will thereupon be free to act to bring tooth 146 of pawl arm 116 into engagement with the driving ratchet 97.

The rotation of driving ratchet 97 will carry pawl arm 116 sharply toward the left (as viewed in Fig. 1) which action will cause, through pivot 117, printing hammer lever 118 to be rotated sharply in a clockwise direction against the tension of spring 120 to impinge platen 144 against the proper character on the type wheel corresponding to the code signal received. In this manner, the characters on the type wheel are caused to be printed while the type wheel is in motion or "on the fly." As previously mentioned, the leftward movement of pawl arm 116 will cause, through the striking of arm 132 against stop 131, the pawl arm 116 to be rotated counterclockwise, disengaging pawl tooth 146 from ratchet 97, permitting ratchet 97 to continue its rotation until shaft 76 is stopped by the engagement of arm 85 of the clutch release lever 75 and portion 88 of the flange 83, and also to restore arm 115 into latching engagement initially with either detent 123 or latch 124, and subsequently to bring shoulder 121 into engagement with detent 123 in the previously mentioned manner.

It is understood that during normal operation of the apparatus, the constituent parts move rapidly, and accordingly, the seeker levers 60, which have fallen into corresponding notches in the code discs 91, are immediately thereafter cammed out by the inclined surface of the cam notches and in so doing the momentum imparted to the seeker levers 60 by this camming out action is transmitted to the cradle 99, which is thrust sharply in a counterclockwise direction suffi-

ciently to permit portion 111 of depending arm 109 to be reengaged by shoulder 137 of latch 133, thus preventing further coaction by the seeker levers 60 and code discs 91 until a new code combination of signals is received; that is, with the arrangement according to the present invention, the printing of more than one character per cycle is prevented.

Modification

A further feature of the present invention resides in the provision of a toggle printing mechanism, as shown in Fig. 8. In this form of printing mechanism, portion 111 of depending arm 109 of the cradle 99 acts to initiate the operation of a toggle printing mechanism, instead of the printing mechanism for effecting the fly printing as disclosed in the principal embodiment of the invention. In this form of the invention, the cradle 99, when acted upon by cam 90, will set the latch 133 in the manner described in connection with the principal form of the invention. With the latch 133 so conditioned as to have shoulder 137 thereof engaged by the latch lever 142 and the seeker levers 60 in contactual engagement with the peripheries of the code discs while performing the seeking function, the cradle 99 (when the seeker levers 60 are set in accordance with a received code combination have found a corresponding arrangement of wards and notches in the code discs) will be actuated sharply in a clockwise direction by the action of spring 138 so that portion 111 will, in the presently described form of printing mechanism, act upon a latch lever 162 to rotate it against the action of its spring 163 out of engagement with arm 164 of a toggle lever 165 pivoted at 166 to the front plate 96.

Upon becoming thus disengaged, lever 165 will be swung sharply in a clockwise direction by a spring 167 extended between vertical arm 168 of toggle lever 165 and a spring post (not shown) attached to front plate 96. Pivoted at the extremity of arm 168 is a toggle link 169, to the extremity of which is pivoted the free end of a printing lever 171 pivoted at 172. Thus during the toggling action of lever 165 and link 169, printing lever 171 is rotated slightly in a counterclockwise direction sufficiently to bring a platen 173 integral therewith against the selected character on the type wheel 98. Lever 171 also carries a stabber 174 which cooperates with a star wheel 175 so that at the instant of printing, the type wheel 98 is maintained momentarily with the selected character in printing position. To compensate for this, the type wheel and star wheel are yieldably connected to the shaft 76, in a manner similar to that disclosed in United States Patent No. 2,181,708, issued Nov. 28, 1939, to A. H. Reiber, so that the shaft 76 may continue in its rotation, and upon completion of the printing operation, the type wheel and star wheel will be returned to their proper angular position with relation to the shaft 76.

To restore the toggle mechanism to its operative position after printing, the cam 94 on shaft 76 is provided with a reset lever 176 pivotally mounted on the plate 96. Reset lever 176 is provided with a cam follower arm 177 and a reset arm 178, the latter arm coacting with an arm 179 integral with the toggle lever 165. Cam 94 is disposed on shaft 76 substantially in the angular position as shown in Fig. 8, when said shaft is in its stop position. Upon initiation of rotation of shaft 76 during the printing operation, cam 94

will rotate clockwise, and at a predetermined instant in the cycle when latch 162 is stripped out of engagement with arm 164 as previously described permitting toggle lever 165 to swing toward the right under the action of its spring 167, the arm 179 integral with toggle lever 165 will coact with the depending arm 178 of the reset lever 176 to swing said reset lever 176 in a counterclockwise direction against the action of its spring 181. Near the end of the operative cycle, cam 94 will coact with arm 177 of the reset lever 176 imparting to the reset lever 176 clockwise rotation which, through arm 178, will impart counterclockwise rotation to toggle lever 165 against the action of its spring 167 to bring arm 164 again into latching engagement with latch 162 preparatory to the initiation of a succeeding printing operation.

Although the present invention has been disclosed in connection with certain specific embodiments thereof, it is understood that such embodiments are merely illustrative and not restrictive and that all forms coming within the scope of equivalency of the appended claims are intended to be covered by the invention.

What is claimed is:

1. In a printing telegraph receiver, a shaft, a type wheel carried by said shaft, a series of code discs affixed to said shaft, a single magnet selecting means, a plurality of seeker members selectively positionable under the control of said means for cooperation with said code discs, means for positioning said seeker members whereby the selective position of the type wheel is determined, and a printing mechanism initiated into operation under the direct control of said positioning means in response to the cooperation between said seeker members and said code discs to cooperate with said type wheel for recording.

2. In a telegraph printer, a type wheel, a printing hammer coacting with said type wheel, a plurality of discs fixedly related to each other, said discs being notched in permuted manner determinative of the positions of the characters on the type wheel, means responsive to received code combinations of signaling impulses, a plurality of seeker levers, and means for positioning said levers permutably in accordance with the operation of said means whereby the selective position of the type wheel is determined, said means effective directly upon the presentation of a code in said discs corresponding to the setting of said levers for releasing said printing hammer for coaction with said type wheel.

3. In a telegraph printer, a type wheel, a printing hammer coacting with said type wheel, means for operating said hammer, a plurality of discs fixedly related to each other, said discs being notched in permuted manner determinative of the positions of the characters on the type wheel, a plurality of seeker levers, a selector means for controlling the permutable setting of said levers in accordance with received code combinations of signaling impulses, and means for positioning said levers permutably in accordance with the operation of said means whereby the selective position of said type wheel is determined, said means effective directly on said hammer operating means upon the presentation of a code in said discs corresponding to the setting of said levers for releasing said hammer operating means for coaction with said type wheel.

4. In a printing telegraph receiver, a shaft carrying a type wheel, a series of discs fixedly related to each other and carried by said shaft,

said discs being notched in permuted manner determinative of the positions of the characters on the type wheel, a single magnet selecting means, a plurality of seeker members selectively positionable under the control of said means for cooperation with the coded peripheries of said code discs, means for positioning said seeker members whereby the selective position of the type wheel is determined, and a printing mechanism including a toggle device, said device controlled by said seeker members to effect the operation of said printing mechanism.

5. In a printing telegraph receiver, a shaft carrying a type wheel, a series of code discs affixed to said shaft, selecting means, a plurality of seeker members selectively positionable under the control of said means, means for positioning said seeker members whereby the selective position of the type wheel is determined, a printing mechanism, and a latch means for said printing mechanism, said latch means controlled directly by said positioning means in response to the cooperation between said seeker members and said code discs for initiating the operation of said printing mechanism.

6. In a printing telegraph receiver, a shaft carrying a type wheel and a ratchet, a series of code discs affixed to said shaft, selecting means, a plurality of seeker members selectively positionable under the control of said means, means for positioning said seeker members whereby the selective position of the type wheel is determined, a printing mechanism including a spring-actuated pawl member, and means controlled by said seeker members in cooperation with said code discs for releasing said pawl member for coaction with said ratchet to effectuate the operation of said printing mechanism.

7. In a printing telegraph receiver, a shaft carrying a type wheel, a series of code discs affixed to said shaft, a single magnet selecting means comprising a plurality of cam members, a selector member and latch member individual to each of said cam members, means whereby said cam members operate said selector members or said latch members in response to received signals, a plurality of seeker members, means for transferring the selection from said selector members to said seeker members, and printing mechanism effective in response to the cooperative action between said code discs and said seeker members to coact with said type wheel to effect printing.

8. In a printing telegraph receiver, a type wheel, a single magnet selector mechanism comprising a plurality of cam members, a selector member and latch member individual to each of said cam members, means whereby said cam members operate said selector members or said latch members in response to received impulses, a plurality of seeker members, means for transferring the selection from said selector members to said seeker members, a series of discs fixedly related to each other, and notched in permuted manner determinative of the positions of the characters on said type wheel, and a printing mechanism controlled by the cooperative effect between said seeker members and the permuted arrangement of notches in said discs for printing from said type wheel.

9. In a printing telegraph receiver, a shaft carrying a type wheel, a series of code discs affixed to said shaft, a selecting means, a plurality of seeker members selectively positionable under the control of said means for cooperation with said

code discs, means for positioning said seeker members whereby the selective position of the type wheel is determined, a toggle printing means, and means effective under the control of said seeker members for operating said toggle printing means to effect the printing operation.

10. In a printing telegraph receiver, a shaft carrying a type wheel, a series of code discs affixed to said shaft, a single magnet selecting means, a plurality of seeker members, means for transferring the selective condition from said selecting means to said seeker members whereby the selective position of said type wheel is determined, a printing mechanism, and means effective in response to the cooperative action between said code discs and said seeker members for determining the instant of operation of said printing mechanism.

11. In a printing telegraph receiver, a type wheel, a single magnet selector mechanism comprising a plurality of cam members, a selector member and latch member individual to each of said cam members, means whereby said cam members operate said selector members or latch members in response to received impulses, a plurality of seeker members, means for transferring the selection from said selector members to said seeker members, a series of discs fixedly related to each other, and notched in permuted manner to correspond to the permutable settings of said seeker members under the control of said selecting means determinative of the positions of the characters on said type wheel, a toggle printing means, and means effective under the control of said seeker members upon the cooperation of said seeker members with the coded peripheries of said code bars for operating said printing means to effect the printing operation.

12. In a printing telegraph receiver, a shaft carrying a type wheel, a series of code discs affixed to said shaft, a single magnet selecting means, a plurality of seeker members, means for transferring the selective condition from said selecting means to said seeker members whereby the selective position of said type wheel is determined, a toggle printing means, and mechanism effective in response to the cooperative effect between said code discs and said seeker members for operating said printing means to effect the printing operation.

13. In a printing telegraph receiver, a shaft carrying a type wheel and a ratchet, a series of code discs affixed to said shaft, a single magnet selecting means, a plurality of seeker members, means for transferring the selective condition from said selecting means to said seeker members whereby the selective position of said type wheel is determined, a printing mechanism including a spring actuated pawl member, means effective in response to the coaction between said code discs and said seeker members for releasing said pawl member for cooperation with said ratchet, and means responsive to the coaction between said pawl and said ratchet to effect the printing operation.

14. In a printing telegraph receiver, a shaft carrying a type wheel and a ratchet, a series of code discs affixed to said shaft, a single magnet selecting means comprising a plurality of cam members, a selector member and latch member individual to each of said cam members, means whereby said cam members operate said selector members or latch members in response to received signals, a plurality of seeker members, means for transferring the selective condition

from said selector members to said seeker members whereby the selective position of said type wheel is determined, a printing mechanism including a spring-actuated pawl member, and means effective in response to the coaction between said code discs and said seeker members for releasing said pawl member for cooperation with said ratchet to effectuate the operation of said printing mechanism.

15. In a printing telegraph receiver, a shaft carrying a type wheel and a ratchet, a series of code discs affixed to said shaft, a single magnet selecting means, a plurality of seeker members, means for transferring the selective condition from said selecting means to said seeker members whereby the selective position of said type wheel is determined, a printing mechanism including a spring actuated pawl member, means effective in response to the coaction between said code discs and said seeker members for releasing said pawl member for cooperation with said ratchet to effectuate the operation of the printing mechanism, and means for limiting the period of cooperation between said pawl and said ratchet.

16. In a printing telegraph receiver, a shaft carrying a type wheel and a ratchet, a series of code discs affixed to said shaft, a single magnet selecting means comprising a plurality of cam members, a selector member and latch member individual to each of said cam members, means whereby said cam members operate said selector members or latch members in response to received signals, a plurality of seeker members, means for transferring the selective condition from said selector members to said seeker members whereby the selective position of said type wheel is determined, a printing mechanism including a spring-actuated pawl member, means effective in response to the coaction between said code discs and said seeker members for releasing said pawl member for cooperation with said ratchet to effectuate the operation of said printing mechanism, and means for limiting the period of cooperation between said pawl and said ratchet.

17. In a printing telegraph receiver, a shaft carrying a type wheel and a ratchet, a series of code discs affixed to said shaft, a single magnet selecting means, a plurality of seeker members selectively positionable under the control of said means, means for positioning said seeker members whereby the selective position of the type wheel is determined, a printing mechanism including a spring-actuated pawl member, means controlled by said positioning means in response to the cooperation of said code discs and said seeker members for releasing said pawl member for coaction with said ratchet to effectuate the operation of said printing mechanism, and means for limiting the period of coaction between said pawl and said ratchet.

18. In a printing telegraph receiver, a shaft carrying a type wheel, a series of code discs affixed to said shaft, a single magnet selecting means, a plurality of seeker members, a cradle for carrying said seeker members, a spring-actuated latch individual to each seeker member carried by said cradle for latching the seeker members in selective position, means for rocking said cradle to effect the transfer of the selective condition from said selecting means to said seeker members whereby the selective position of said type wheel is determined, and means controlled by said cradle in response to the cooper-

ative effect between said code discs and said seeker members to effect printing from said type wheel.

19. In a telegraph printer, a type wheel, a printing hammer coacting with said type wheel, a control mechanism for said printing hammer, a plurality of discs fixedly related to each other, said discs being notched in permuted manner determinative of the positions of the characters on the type wheel, a plurality of seeker levers, a single magnet selector means for controlling the operation of said levers permutably in accordance with received code combinations of signaling impulses, and means effective upon the presentation of a code in said discs corresponding to the setting of said levers for releasing said printing hammer control mechanism for operation.

20. In a printing telegraph receiver, a shaft carrying a type wheel and a ratchet, a series of code discs affixed to said shaft, a single magnet selecting means, a plurality of seeker members selectively positionable under the control of said means, means for positioning said seeker members whereby the selective position of the type wheel is determined, a printing mechanism including a spring-actuated pawl member, and means controlled by said seeker members for releasing said pawl member for coaction with said ratchet to effectuate the operation of said printing mechanism.

21. In a telegraph printer, a shaft carrying a type wheel and a ratchet wheel, a printing hammer coacting with said type wheel, a series of code discs affixed to said shaft, a single magnet selecting means, a plurality of seeker members selectively positionable under the control of said means, a printing mechanism including a spring-actuated pawl member, means controlled by the cooperation of said code discs and said seeker members for releasing said pawl member for coaction with said ratchet wheel to effectuate the operation of said printing hammer, means for limiting the period of coaction between said pawl member and said ratchet wheel, and means for varying the printing blow of said printing hammer.

22. In a telegraph printer, a type wheel, a printing hammer coacting with said type wheel, means for operating said printing hammer, a plurality of code discs fixedly related to each other, said code discs being notched in permuted manner determinative of the positions of the characters on the type wheel, a plurality of seeker levers, a selector means for controlling the permutable setting of said levers in accordance with received code combinations of signaling impulses, means for setting said seeker levers as determined by said selector means, means effective directly on said first recited means upon the presentation of a code in said discs corresponding to the setting of said levers for releasing said printing hammer operating means for recording, and means for varying the printing blow of said printing hammer.

23. In a printing telegraph receiver, a shaft carrying a type wheel, a series of code discs affixed to said shaft, selecting means, a plurality of seeker members, means cooperable with said selecting means to condition said seeker members for selective operation with said code discs, a printing mechanism, latch means for said printing mechanism, and means controlled directly by said conditioning means for tripping said latch

means to initiate operation of said printing mechanism for printing from said type wheel.

24. In a printing telegraph receiver, a single magnet selector mechanism comprising a plurality of cam members, a selector member and latch member individual to each of said cam members, means whereby said cam members operate said selector members or said latch members in response to received impulses, a plurality of seeker members, means for transferring the selection from said selector members to said seeker members, a shaft carrying a type wheel and a series of discs affixedly related to each other, said discs being notched in permuted manner determinative of the positions of the characters on said type wheel, and a printing mechanism controlled by the cooperative engagement between said seeker members and said code discs for printing from said type wheel.

25. In a printing telegraph receiver, a shaft, a type wheel carried by said shaft, a series of code discs affixed to said shaft, a single magnet selecting means, a plurality of seeker members, means to render said seeker members permutably positionable under the control of said selecting means for cooperation with said code discs, and a toggle printing mechanism controlled by said seeker members for printing from said type wheel.

26. In a telegraph printer, a type wheel, a toggle printing means coacting with said type wheel, a plurality of discs fixedly related to each other, said discs being notched in permuted manner determinative of the positions of the characters on the type wheel, a plurality of seeker levers, means for operating said levers permutably in accordance with received code combinations of signaling impulses, and means effective upon the presentation of a coded arrangement of notches in said discs corresponding to the selective positioning of said levers for releasing said toggle printing means for operation.

27. In a printing telegraph receiver, a type wheel, a ratchet cooperably related to said type wheel, a series of code discs one for each element of the code operatively associated with said type wheel, means for rotating said type wheel, selecting means, a plurality of members, means under control of said selecting means for causing said members to cooperate with said discs, and a printing mechanism including a spring-actuated pawl member controlled by the cooperation of said members with said discs, said third recited means acting in response to said cooperation to release said pawl member for actuation by said ratchet to effect the printing operation.

28. In a printing telegraph receiver, a shaft, a type wheel carried by said shaft, a series of code discs affixed to said shaft, a single magnet selecting means, a plurality of seeker members, means to render said seeker members selectively positionable under the control of said selecting means for cooperation with said code discs, and a ratchet and pawl operated printing mechanism controlled by said seeker members for printing from said type wheel.

29. In a printing telegraph receiver, a type wheel, a printing hammer coacting with said type wheel, ratchet and pawl means for operating said hammer, a plurality of discs fixedly related to each other, said discs being notched in permuted manner determinative of the positions of the characters on the type wheel, a plurality of seeker levers, means for operating said levers permutably in accordance with received code combinations of signaling impulses, and means effective

upon the presentation of a code in said discs corresponding to the actuation of said levers for controlling the operation of said ratchet and pawl means to effectuate the printing operation.

30. In a printing telegraph receiver, a shaft carrying a type wheel, a series of code discs fixed to said shaft, a plurality of seeker members, means to control the setting of said seeker members permutationally, means to cause said seeker members to sense the peripheries of said code

discs, said discs coded in permuted manner such that each permutational setting of said seeker members will find first a code in said discs individual to the type character corresponding to said setting, a printing mechanism, and means effective directly in response to the coaction between said seeker members and said discs during the process of sensing for initiating the operation of said printing mechanism.

HOWARD L. KRUM.
